US0D1098970S

(12) **United States Design Patent** (10) Patent No.: **US D1,098,970 S**
(45) Date of Patent: ** Oct. 21, 2025

(54) **MOBILITY SCOOTER**

(71) Applicant: **Zhejiang Weiling New Energy Technology Co., Ltd.**, Taizhou (CN)

(72) Inventor: **Zhe Zhang**, Zhejiang (CN)

(**) Term: **15 Years**

(21) Appl. No.: **35/522,896**

(22) Filed: **Oct. 8, 2024**

(80) **Hague Agreement Data**

Int. Filing Date: **Oct. 8, 2024**

Int. Reg. No.: **DM/241505**

Int. Reg. Date: **Oct. 8, 2024**

Int. Reg. Pub. Date: **Nov. 8, 2024**
